UNITED STATES PATENT OFFICE.

JOHN H. EATON, OF ROCHESTER, NEW YORK, ASSIGNOR OF ONE-THIRD TO JAMES F. EATON, OF ROCHESTER, NEW YORK.

INTERNAL-COMBUSTION ENGINE.

1,037,605.

Specification of Letters Patent. Patented Sept. 3, 1912.

Application filed April 29, 1908. Serial No. 429,835.

To all whom it may concern:

Be it known that I, JOHN H. EATON, of Rochester, in the county of Monroe and State of New York, have invented certain new and useful Improvements in Internal-Combustion Engines; and I do hereby declare the following to be a full, clear, and exact description of the same, reference being had to the accompanying drawings, forming a part of this specification, and to the reference-numerals marked thereon.

The present invention relates to rotary internal combustion engines and it has for an object to provide a construction in which a change may be made in the compression of the explosive mixture in order that the engine may be adapted to a large variety of different grades of fuel to obtain the best results from the fuel used. Other objects are to provide improved means for feeding the fuel to and discharging the burned gases from the cylinders; and to maintain the parts in a cooled state.

To these and other ends the invention consists in certain improvements and combinations of parts all as will be hereinafter more fully described, the novel features being pointed out in the claims at the end of the specification.

In the drawings: Figure 1 is a side view of an engine constructed in accordance with this invention; Fig. 2 is an end view of the same engine; Fig. 3 is a section on line 2—2 and also on line 3—3, Fig. 1; Fig. 4 is a plan view with parts in section; Fig. 5 is a detail view of the connection between the connecting rods and the eccentrically mounted thrust stud; and Fig. 6 is a detail view of the control for the igniting mechanism. Fig. 7 is a section on line 7—7 of Fig. 4; Fig. 8 is a section on line 8—8 of Fig. 4; Fig. 9 is a section of the inlet and exhaust casing with the hub in elevation; Fig. 10 is a detail view showing the connection of the piston with the thrust member.

Referring particularly to the drawings D indicates the shaft to be driven, mounted upon a suitable base or frame A. Connected to one end of this shaft by a spider frame or spokes H is a rim E which serves as a fly wheel and at the same time as a rotary support for the cylinders. The cylinders J of which there may be any de-

sired number, in the present instance four, are arranged in two sets, radially to the shaft D, being bolted at d to the interior of the rim between the spokes H. Within these cylinders work the pistons P which by connecting rods K are connected to a thrust stud or member C arranged eccentrically to the axis of the rotary support. The connection between the connecting rods and the stud C may be of any suitable construction but it is preferred to provide shoes K' having curved faces to rock on stud C, the outer faces of the shoes being tapered at opposite ends K² in order that rings K³ may surround all of the shoes at each end to secure them on the stud, bolts K⁴ being employed to hold the rings in position.

I may cause a change in the displacement of the pistons in the cylinders to produce a change in the compression of the fuel, while the engine is in operation, or while it is still. This may be effected by shifting the stud or thrust member C in a direction radial to the shaft D. For this purpose stud C is mounted on a bearing block B guided on the frame A, and the movement of the block is effected by a screw shaft F operated by a hand wheel Z. It is apparent that the thrust stud C may be moved so that it is axially aligned with the shaft D in which event no movement of the pistons P takes place; or that said stud may be moved so that the pistons at one end of their movement reach nearly to the heads of their cylinders.

The explosive mixture may be admitted through valve casings a which are connected to ports in the ignition or explosion chambers of cylinders J and valves v are arranged in the casings and are normally closed by spring w. These valves open on the suction stroke of the pistons and the explosive mixture is drawn from the pipes b which connect two valve casings a and are connected to pipes b' which are in turn connected to ports or channels b² formed in the hub of the fly wheel. The ports or channels b² lead to an annular chamber b³ to which the inlet I is connected.

The exhaust is effected through passages c, which connect adjacent exhausts and have passages c' connected to ports or channels c² in the hub between channels b², and these

channels c^2 are connected by lateral ports c^3 with an annular chamber c^4 connected with the main exhaust O. Chambers b^3 and c^4 are formed in a single casting O' which is stationarily supported about the hub of the fly wheel, one end having the shaft D turning therein and the other end carrying a packing r which prevents the escape of gases at this point.

- 10 In order that the driven shaft and other parts of the engine adjacent to the exhaust may be maintained in a cooled state, I may make a portion of the driven shaft D hollow and at one end of the hollow portion I
 15 may provide an annular chamber W suitably packed about the shaft and connected to a pump R. This pump is connected to a suitable water supply and is operated by an eccentric Q on the drive shaft. The water
 20 passes from the pump to the chamber W and thence through a lateral port to the interior of the shaft D. The other end of the shaft D is closed and a short distance from this closed end are provided lateral ports D'
 25 which extend through the hub of the fly wheel and connect with a water chamber q surrounding the annular chamber c^4 , from which the water is exhausted. In this manner the hub of the rotary cylinder support
 30 is maintained in a cooled state as is also the casting O'.

The exhaust passages are controlled by valves X, the valves of one set of cylinders the units of which are adjacently arranged being successively operated on one rotation 35 of the rotary support and the valves of the other set being successively operated on the next rotation. For this purpose the valves may be held normally closed by springs k and have arms Y projecting laterally therefrom, and carrying anti-friction rollers, the arms on one set of cylinders being longer 40 than the other two. The valves are operated by two cams S' and T' which are arranged side by side and each of which operates to successively open the valves of one set of adjacent cylinders on every alternate 45 revolution of the cylinders, and for this purpose I may employ devices for shifting the cams. The cam S' is shown in elevation 50 in Fig. 3 but the companion cam T', which is of the same crescent shape, the cam surfaces on each being identical, is behind it in that view and hence does not appear. It
 55 is because of this arrangement that the arms Y of one set of cylinder valves are made longer than the others for it will be seen that the arms which engage the farther cam S' must reach over and clear the inner 60 cam T'.

The devices for shifting the cams preferably comprise a cam carrying member M arranged on driven shaft D and having cam grooves S and T in which move travel-
 ers S^2 and T^2 respectively. The travelers

are respectively connected to slide bars S^3 and T^3 movable longitudinally of the shaft D and carrying the cams S' and T' to which they are rigidly connected in any suitable manner. The cam S' of course must needs be cut away in somewhat the manner shown in Fig. 3 so that the bar T^3 of the cam T', which latter is behind cam S' in the said figure, may pass through it to take its connection. The cam grooves S and T are formed to shift the cams S' and T' alternately into and out of the path of travel of the pairs of rollers on the arms Y, thus permitting the valves at the proper time to remain closed while the pistons move outwardly to compress the mixture and then to open the exhaust valves at proper time for the discharge of exhaust gases.

Bearing in mind the fact that the exhaust valve arms Y of one set of adjacent cylinders coöperate with their cam S' or T' in one plane and the other set in another, it will be seen that either cam may be shifted into or out of such plane and hence into and out of operative position with respect to its coöperating arms independently of the other cam. This is necessary in view of the fact that the present engine is of the four cycle type, and the respective sets of adjacent cylinders exhaust upon every other revolution instead of every revolution. Furthermore, the cams S'—T', as shown in Fig. 3, are semi-circular and as there are four arms Y, equidistantly spaced, one of them at least, and often two, are within such semi-circle all the time. Obviously neither cam can be shifted while an arm is in engagement therewith and, therefore, the cams are shifted alternately, one upon each revolution of the engine while its arms are on the other side of the circle.

It is thought desirable to give at this point, an explanation of the cycle of the engine to assist in a proper understanding of the cam arrangements just described. Adjacent cylinders forming each set to which allusion has been made, are exhausted in the same revolution throughout half of its duration, while their arms Y are in the half circle controlled by the cam and subsequent operations of the cylinders throughout the four cycles are jointly entered into in the same relationship. In Fig. 3, one set of cylinders is exhausting during the upper half of the first revolution, intaking on the lower half, compressing on the upper half of the next revolution (the cam having been shifted during the interval) and exploding on the lower half thereof. The other set during these operations is respectively intaking, compressing, exploding and exhausting. The explanation is confined to the cylinders by sets inasmuch as the units of each set follow each other very closely but there is, of course, a point between the

half revolutions named in which one of the cylinders of a set is intaking for instance while its mate is still exhausting, these being the positions of the upper and right hand cylinders in Fig. 3.

5 The ignition of the explosive mixture is effected preferably by arranging contact pieces *g* on the periphery of the rim *E* and connecting them to the sparking plugs *h*.
 10 The contact pieces *g* are insulated from each other by an insulating band or strip *y* and have coöperating therewith a stationary brush contact *f* connected to a suitable electric circuit and supported on and insulated
 15 from a yielding arm *e* which is arranged on frame *A*. Connected to the rotary support to turn therewith is a ring *G* which carries two series of contacts *L*, one set being arranged in a plane transverse to the axis of
 20 the rotary support, different from the plane in which the other set is arranged so that a contact *N* may be moved to successively engage either series. The contact *N* is connected to the electric circuit before mentioned, and is supported on an arm *U'*
 25 which is rotatably mounted on a cylindrically turned portion *U²* of slide *U*, but it is suitably locked to move longitudinally with the slide. Slide *U* is movable on the
 30 guide *i* in the direction of the axis of the rotary support and carries a traveler *V* movable in the cam groove *S* on cam member *M*.

In order that the time of the engagement
 35 of the contact *L* may be changed, the contact *N* is mounted to shift in the direction of the path of movement of the contact *L* and for this purpose turns on the slide *U*. This shifting is effected by a controlling lever *n*
 40 which also turns loosely on the rounded portion *U²* of the slide *U* being admitted through a cut away portion in the guide *i* so that it simply utilizes the guide as a pivot, the latter at the same time being movable therethrough. The lever is slidably
 45 connected to arm *U'* by a guide *j* that preferably passes through an aperture therein and which causes the arm *U'* to rotate with the lever but at the same time permits it to move with the longitudinal movement of the slide relatively thereto. To hold the lever and the contact *N* in their adjusted positions the lever carries a hand operated clamp screw *p* which works through a slot
 55 in upright bracket *m* on frame *A*.

The lubrication of the cylinders may be effected by means of a lubricant chamber *x* from which leads a tube *u* to direct fluid to a channeled ring *s* that opens toward its
 60 axis and is connected by short tubes *s'* to the cylinders *J*.

The specific operation of the several parts of this embodiment having been given, at this point it will be necessary only to describe the general operation. Fuel is ad-

mitted to the engine at inlet *I* and is drawn into the cylinders through valves *v*. First the cylinders of one series are successively charged and during this charging the cylinders of the other series are successively exhausted. The next movement of the pistons of the first mentioned series is to compress the mixture which is ignited when the extreme compression point is reached, the other series of pistons being at the same time moved to charge their cylinders. The explosion causes the pistons to act on the thrust member *C* and rotates the cylinders, their support, and the shaft *D* from which the power is taken. The time of the explosion may be controlled by the lever *n* which when operated shifts contact *N* in the direction of contact *L*.

An engine constructed in accordance with this invention gives maximum power; its parts are arranged so that they are best adapted to withstand the strain due to centrifugal force; and it may be controlled in such a manner that the best effects from the fuel used may be obtained.

What I claim is:

1. The combination with a rotary support, of a plurality of cylinders carried thereby and forming two sets, pistons working in the cylinders, a member to which the pistons are connected arranged eccentrically to the axis of the rotary support, valves for said cylinders, a pair of cams for operating the valves, one for each set of cylinders, and means for shifting the cams alternately into and out of operating position.

2. The combination with a rotary support, a set of cylinders carried thereby, pistons for operation in the cylinders, and a thrust member for operating the pistons, of valves for the cylinders, a slidably mounted cam for successively operating said valves, and a rotary cam for effecting the movement of the sliding cam toward and from operative position.

3. The combination with a rotary support, of a plurality of cylinders carried thereby and forming two sets, pistons working in the cylinders, valves for said cylinders, a pair of slides, cams carried by the slides, one for operating the valves of each set, and a rotary cam member adapted to shift the slides alternately into operative relation with the valves.

4. The combination with a driven shaft, of a support carried thereby, to rotate therewith, a plurality of cylinders forming two sets, carried by the support and having pistons working therein, valves for said cylinders, arms extending from the valves, the arms from the valves of the two sets of cylinders operating in different planes parallel with the plane of rotation of the support, a pair of slides, cams carried by the slides, and a cam member on the shaft op-

erating the slides to shift the cams alternately each into the path of its respective coöperating arms.

5. The combination with a hollow shaft, of a rotary support secured to the shaft and having a hub provided with exhaust passages, a plurality of cylinders carried by the rotary support and communicating with the exhaust passages, and a member in which

said hub turns, having an exhaust chamber communicating with the exhaust passages in the hub and a water chamber surrounding the exhaust chamber and communicating with the hollow shaft.

JOHN H. EATON.
